UNITED STATES PATENT OFFICE.

TUCKER EARLE MILLER, OF NORMAN, OKLAHOMA TERRITORY.

SIGNALING APPARATUS FOR THEATERS, &c.

No. 796,920.

Specification of Letters Patent.

Patented Aug. 8, 1905.

Application filed February 4, 1905. Serial No. 244,182.

To all whom it may concern:

Be it known that I, TUCKER EARLE MILLER, a citizen of the United States, residing at Norman, in the county of Cleveland and Territory of Oklahoma, have made certain new and useful Improvements in Signaling Apparatus for Theaters, &c., of which the following is a specification.

My invention is in the nature of a mechanical signaling device for theaters, opera-houses, &c., designed to reduce to a simple, quiet, and well-organized system the transmission and execution of the various orders incident to the dropping of curtains, the setting of scenes, orders to the orchestra, dressing-room, head usher, electricians, grippers, &c., instead of having to rely upon verbal orders and the despatch of messengers.

In many cases, as in the event of fire, the shouting of orders and hurrying of messengers is liable to start or increase the very panic which it is desired to avoid, and in such cases my apparatus secures the prompt dropping of the asbestos curtain, the opening of exits, &c., without any noise or excitement in a prompt and effective way before the audience can know anything of the preparations made for its safety.

My invention consists in the novel construction and arrangement of a signaling apparatus comprehending an operator's transmitting-board, a receiving-board, and intermediate mechanism whereby the above results are carried out, as will be hereinafter fully described.

In the particular application shown I have arranged the various features of the apparatus for connection between the operator's transmitting-board located at or near the stage-level and a receiving-board in the "fly-gallery," of which—

Figure 1 is an interior view of the stage looking outwardly toward the auditorium and showing the location of my signal apparatus. Fig. 2 is a front, and Fig. 2^a a sectional side, view of one of the units of the operator's transmitting-board, which is located near the stage-level. Fig. 3 is a front view, and Fig. 3^a a sectional side view, of one unit of the receiving-board, which is located in the fly-gallery. Fig. 3^b is an enlarged sectional view of a portion of one of the units of the receiving-board, and Fig. 4 is a face view of the complete receiving-board.

In the drawings, Figs. 1, 2, and 3, A A' B C represent one complete vertical unit of my signal apparatus. These units are repeated

in parallel position side by side to any desired extent. As shown in Figs. 1 and 4, there are ten. The upper portion of each unit consists of a vertically-elongated signal-box A, whose front is provided with a series of windows a, in which are made to appear sliding panels a', Figs. 3, 3^a, and 3^b, and from which windows said panels may be made to disappear. These panels bear each its own order in plain letters. In Fig. 3 only two panels are exposed, while in Fig. 4 all are exposed, so as to fully show the nature of the orders. The panel is raised to its exposed position by a separate pull-wire B for each, which wires pass over pulleys b b' at the top and are attached to the sliding panels.

Below the signal-section A is the weight-box A', in which is arranged a separate weight D or D', Fig. 3^a, for each signal-panel, the weights being connected to the panels by the wires B' and arranged by their gravity to bring down each panel to its invisible position after having been raised by the pull-wires B.

The lower portion of each unit consists of section C, Figs. 2 and 2^a, and a series of these in parallel vertical position (see Fig. 1) form the operator's transmitting-board. The sections of this board correspond in number and position to the sections A A' above and, as shown, are ten in number, each section C being connected by its group of wires B with its corresponding section A A' above.

The signal-receiving board A A' is located in elevated position in the fly-gallery in position for easy observation by the attendant in charge in the fly-gallery, and the operator's transmitting-board C is located down upon or near the level of the stage, so that the operator may have a comprehensive view of the same and be fully advised of what is going on and what is required to be done.

Each vertical unit-section C of the operator's transmitting-board has a vertical series of holes in front, through which the various wires B of the corresponding unit-sections A A' pass to the front, (see Figs. 2 and 2^a), going around small pulleys c and c' and terminating each in a pull-ring e, with rubber cushion-stop e', which prevents the weight above from drawing the lower end of the wire into the case. The rings e form handles for the operator, and by pulling out the same the weights in weight-box A' are lifted, one at a time, and the attached signal-panels are brought to the exposed position in the window-openings. When any signal-panel has

been thus exposed by the pulling of the handle-rings *e* by the operator, such panel is maintained in such exposed position by fastening the ring *e* upon the downturned hook *h*, of which there is one for each handle-ring on the face of the operator's board. Under each handle-ring is printed or painted on the face of the unit-section *C* the order to be executed by the attendant in the fly-gallery. For lack of space these orders are, in Fig. 2, displayed at the side, and on the face of the movable signal-panels in the unit-section *A* in the fly-gallery is printed or painted the corresponding order to be executed, each signal-panel above having its individual pull-ring in the operator's transmitting-board below.

The signal-panels (see Fig. 3^b) have recessed faces and bear grooved guideways *g g*, in which are slipped cards bearing the printed order, which cards are interchangeable and may be taken out and replaced when desired.

To prevent a too great elongation of the receiving-board in the fly-gallery, it is made double with the panels in two vertical series, as seen in Figs. 3^a and 3^b, one in front of the other, but each showing through its own window, the two series being provided with separate sets of weights and interference being avoided by a middle partition *p*, in which also are arranged window-openings for the rear series of signal-panels.

To give a signal to the fly-gallery, the operator pulls down the ring on the operator's board and hooks it over hook *h*. The first signal is, as seen in Fig. 4, "Act 1." The second signal in the same section is "Advertisement curtain." If at the close of an act the advertisement-curtain is to fall, the operator at the end of this act pulls the ring on the operator's board indicating that curtain, and this action raises the signal-panel in the fly-gallery bearing the words "Advertisement curtain." The operator then pulls the ring marked "Down" and it sets the corresponding signal in the fly-gallery board. Then, as is customary in all theaters and opera-houses to give warning before a curtain is raised or lowered, the operator pulls the signal marked "Warning," and when the warning-signal disappears in the fly-gallery the curtain is lowered. The other signals are transmitted and the orders executed in a similar way.

Having thus described my invention, what I claim as new, and desire to secure by Letters Patent, is—

1. A signaling apparatus for theaters, &c., comprising an operator's transmitting-board, a receiving-board and intermediate connecting-wires, the receiving-board being made

with separate box units arranged side by side, each unit consisting of a vertical box having a vertical series of window-openings and a vertical series of sliding signal-panels, and the operator's board being formed of separate box units arranged side by side, each unit consisting of a vertical box bearing pull-handles and holding devices arranged in vertical series, the pulls of each unit of the operator's board being individually connected to the corresponding panels of each unit of the receiving-board, and the panels of the receiving-board and the operating-pulls of the operator's board being each marked with corresponding orders substantially as and for the purpose described.

2. A signaling apparatus for theaters, &c., comprising the combination of an operator's transmitting-board, a receiving-board and intermediate connecting-wires, the receiving-board being made with separate box units arranged side by side each unit consisting of a vertical box having a vertical series of window-openings and a vertical series of sliding signal-panels and located in the fly-gallery, and the operator's board being arranged below the same near the stage level and being formed of separate box units arranged side by side, each unit consisting of a vertical box bearing pull-handles and holding devices, arranged in vertical series and intermediate wires running from the receiving-board in the fly-gallery to the operator's board near the stage level, the panels and pulls of the vertical units of both boards being individually connected and bearing corresponding orders substantially as described.

3. In a signaling apparatus for theaters, &c., a receiving-board composed of a series of separate box units, each unit having a vertical partition forming two chambers, one in front of the other and each having window-openings in front, two series of sliding signal-panels arranged one in front of the other, individual means for raising these panels and individual weights for lowering the same substantially as described.

4. In a signaling apparatus for theaters, &c., a signal unit comprising a vertical box containing a vertical series of windows and a vertical series of sliding panels and weights, a vertical box with a vertical series of holes, pulls, and hooks, wires connecting the pulls of one box with the panels of the other box and pulleys for guiding the wires substantially as described.

TUCKER EARLE MILLER.
